checks, and when so folded or closed the register booklet is maintained at the open position in which it was last used or the front portion 10 may be folded toward the opposite side of the 5 back portion, as shown in Fig. 2, when the register is to be used. In the latter position the connecting portion 12 supports the edge of the back portion 11 farthest from the person using the register in raised position, thus causing 10 the back portion to slope downwardly toward the user at an angle which contributes to ease and convenience in using the register.

It is apparent that I have invented a novel, 15 simple, efficient and convenient form of check register wherein the single column system employed eliminates cross footing, machine footing and cross reference, wherein entering of transactions other than the writing of checks may be effected without interfering with consecutive 20 numbering of checks, wherein space for entering the details of distribution of the amounts covered by a check is provided in close association with space for registry of the check, whereby it is possible that all transactions be carried direct 25 to the ledger without running the items through the cash book, wherein the inconvenience of thumbing over tightly bound check stubs is eliminated, and whereby simplicity, speed, accuracy and practicability are accomplished and 30 inconvenience and labor minimized.

It will, of course, be understood that various changes may be made in the form, details and arrangement of the columns, without departing from the scope of my invention, which, generally stated, consists in a device capable of carrying out the objects above set forth and in the novel parts and combinations of parts disclosed and defined in the appended claims. 5

What is claimed is:—

1. In a bank check register, a flat back member adapted to have a check register book secured thereto and means for holding a pad of checks near one of the horizontal edges of said back member so as to be slidable from side to side thereof. 10
2. In a bank check register, a flat back member adapted to have a check register book secured thereto and covering the greater and upper portion thereof, a horizontally extending slide mounted in the lower portion of said back member and extending transversely thereof below the portion of the back adapted to be covered by said check register book and means mounted in said slide for holding a pad of checks, said means being slidable from side to side of said 20 back member. 25
